UNITED STATES PATENT OFFICE.

JOHN H. D. EVERETT, OF WAUKEGAN, ILLINOIS.

SAFETY RAZOR.

Application filed June 9, 1921. Serial No. 476,168.

To all whom it may concern:

Be it known that I, JOHN H. D. EVERETT, a citizen of the United States, and a resident of the city of Waukegan, county of Lake, 5 and State of Illinois, have invented certain new and useful Improvements in Safety Razors, of which the following is a specification.

My invention relates to new and useful 10 improvements in safety razors, and has for its principal object the provision of an improved construction of this character which will be highly efficient in use and capable of economical manufacture. The present invention 15 constitutes an improvement over that which is disclosed in my prior application for improvements in safety razors, filed July 23, 1920.

Other objects will appear hereinafter. 20 The invention consists in the combinations and arrangements of parts hereinafter described and claimed.

The invention will be best understood by reference to the accompanying drawings 25 forming a part of this specification, and in which.

Fig. 1 is a plan view of a blank from which my improved safety razor is formed,

Fig. 2 is a side elevational view of my 30 improved safety razor,

Fig. 3 is a top plan view of the same,

Fig. 4 is a sectional detail view taken substantially on line 4—4 of Fig. 2,

Fig. 5 is a plan view of a safety razor 35 blade embodied in the invention,

Fig. 6 is a detail view taken substantially on line 6—6 of Fig. 3.

In manufacturing my improved safety 40 razor the blade holder 8 and handle 9 is formed from a blank 10 stamped from a single piece of material having integral portions 9' at one end thereof and diverging jaw supporting strips 12' carrying oppositely arranged jaws 14 and 14' joined together 45 by a portion 16. The blank 10 is preferably formed of spring steel so that when the blank is folded symmetrically with respect to a central dividing line of the blank indicated at 11 the jaws 14 and 14' will be permitted to slightly give way from each other to facilitate mounting the razor blade in shaving position on the holder.

The forming of the safety razor is as follows:

55 The integral portions 9' are folded upon each other along the line 11 to form a handle

9 and are secured together by spot-welding or the like. The strip portions 12', constituting the shank 12, are spot welded or secured together by any other suitable means. 60

A portion of the side strips 12' forming the shank 12 are bent or curved away from each other, as at 13, forming a support for the blade holder 8. The jaws 14 and 14' of the blank 10 are then bent substantially at right 65

angles with respect to the outer portions of the strips 12 and 12' and extending substantially parallel to each other forming clamping jaws 15. The lower portions of the clamping jaws 15 are bent or looped out- 70

wardly, as at 15', slightly extending beyond the outer surfaces of the jaws 15, and serving as a guard. The portion 16 of the blank 10 between the loops 15' thus formed, is bent 75

substantially at right angles to the jaws 15 and is provided with serrations or teeth along its outer edge to form a blade guard. Laterally projecting from each of the jaws 15 are projections or lugs 17 each provided on their inner surfaces with a groove 18 for 80

the reception of a safety razor blade 19. The side edges of the safety razor blade 19 are provided with notches 20 and 20' adapted 85

to receive the projections or lugs 17. This arrangement prevents the safety razor blade 19 from a vertical reciprocating movement and the groove 18 prevents laterally withdrawal of the said safety razor blade during 90

its operation. A slit 21 is provided between the handle portions forming the handle 9 in which the safety razor blade 19 is inserted when it is desired to sharpen the same 95

by stropping or otherwise.

In use the razor blade 19 is positioned in the razor blade holder 8 and used in the usual manner. The loops 15' which slightly project beyond the extreme side edges of the safety razor blade 19, guard the corners of the said blade and prevent injuring the 100

face of the user. The material used for forming the safety razor being of a spring steel or the like, will allow the jaws 15 to slightly give outwardly when the said safety razor blade is positioned or removed 105

from the blade holder 8. The projections or lugs 17 prevent the blade from a vertical, reciprocating movement and the grooves 18 which receives the side edges of the safety razor blade 19, prevents laterally withdrawal of the said blade when in operation. 110

In manufacturing my improved safety razor it requires but one operation to punch

the blank from the material, and but a slight operation to shape the said blank into the form heretofore described. My improved safety razor can be manufactured at 5 a small cost and produced in large quantities.

While I have illustrated and described the preferred form of construction for carrying my invention into effect, this is capable of 10 variation and modification without departing from the spirit of the invention. I, therefore, do not wish to be limited to the precise details of construction set forth, but desire to avail myself of such variations and 15 modifications as come within the scope of the appended claims.

Having described my invention, what I claim as new and desire to secure by Letters Patent is:

20 1. In a safety razor, comprising in combination with a safety razor blade having notches formed in its opposite corresponding ends intermediate the edges thereof, of a holder for said blade, said holder comprising a blank struck from a single piece of material having one end portion bent centrally upon itself to form a handle and the other end of said blank comprising diverging jaw supporting portions and oppositely 25 disposed resilient jaws joined together by a serrated portion, said jaws being bent substantially at right angles with respect to said serrated portion; and lateral projections carried by said jaws adapted to engage said notches for holding said blade in shaving position, substantially as described.

2. A safety razor formed of an integral connected blank comprising at one end a handle portion doubled centrally upon itself 40 and at the other end a transverse guard portion, the ends of the guard portion being connected with the handle portion by separated arms, said arms being bent up at the ends of said guard to form spring clamping

45 jaws yielding through the resiliency of said arms to clamp the ends of a razor blade between them in operative relation with said guard, substantially as described.

3. A safety razor formed of an integral connected blank comprising at one end a 50 handle portion doubled centrally upon itself and at the other end a transverse guard portion, the ends of the guard portion being connected with the handle portion by separated arms, said arms being bent up at the 55 ends of said guard to form spring clamping jaws yielding through the resiliency of said arms to clamp the ends of a razor blade between them in operative relation with said guard, grooved lugs projecting from the 60 edges of said jaws to engage notches in the ends of a blade, in combination with a blade having notches in its ends to receive said lugs, substantially as described.

4. A safety razor comprising a blade 65 holder formed from a blank punched from a single piece of material, the sides of said holder being curved symmetrically inwardly and extending parallel with respect to each other to a point where said blank is folded centrally upon itself forming a handle; a safety razor blade having notches in its side edges mounted on said holder; and projections on each of the sides of said 70 holder having grooves on their inner surfaces adapted to be inserted in said notches 75 retaining the said safety razor blade in operative position and preventing vertical or laterally withdrawal of said blade during its operation, substantially as described.

80 In testimony whereof I have signed my name to this specification in the presence of two subscribing witnesses.

JOHN H. D. EVERETT.
